UNITED STATES PATENT OFFICE.

WILLIAM DALTON, OF SCHENECTADY, NEW YORK.

RAIL FASTENER.

Application filed August 17, 1923. Serial No. 657,945.

To all whom it may concern:

Be it known that I, WILLIAM DALTON, citizen of the United States, and resident of Schenectady, in the county of Schenectady, 5 and State of New York, have invented a certain new and useful Improvement in Rail Fasteners, of which improvement the following is a specification.

My invention relates to means for securing railroad rails to metal ties, particularly 10 to ties of I-beam shape, such as old rails.

One of the principal objects of the invention is to provide a rail fastener, in the application of which no openings or cuts are 15 required to be made either in the rails or in the ties.

Another object of the invention is to provide a rail fastener which will securely hold the rail against lateral movement in either 20 direction. It is not necessary, in practice to equip each and every tie with a fastener constructed and adapted to prevent lateral movement of a rail inward towards the companion rail, but the fastener may be applied 25 on, say, only every fourth or fifth tie, so that it will be understood that the fasteners hereinafter described may be combined in practice with simpler fasteners located on the outside of the rails only. In a companion application, filed of even date herewith, Ser. No. 657,944, I have disclosed a form of such simpler fastener.

In the accompanying drawings: Figure 1 is a view, in perspective, of a tie and rails, 35 equipped with one form of fastener, adapted to prevent inward movement of the rail, as well as spreading thereof; Fig. 2, a plan view of portions of a rail and tie of Fig. 1; Fig. 3, a side elevation of the tie and fasteners of Figs. 1 and 2, the rail being shown in section; Fig. 4, a side view, in elevation, of the rail and fastener of Figs. 1 to 3, the tie being shown in section; Fig. 5, a view, in perspective, of a tie and rails, illustrating a 40 structural modification of the fastener; Fig. 6, a partial plan view of Fig. 5; Fig. 7, a side elevation of the same, the tie being in section; Fig. 8, a view, in perspective, as seen from below, of a tie and rail, illustrating an 45 other structural modification of fastener; Fig. 9, a side view of Fig. 8, in elevation, the tie being shown in section; Fig. 10, a side view of Fig. 7, in elevation, the rail being shown in section; Fig. 11, a plan view of the 50 same; Fig. 12, a view, in perspective, of a

tie and rails, illustrating another structural modification of fastener; Fig. 13, a partial plan view of the same and Fig. 14, a side view of the same, in elevation, the rail being shown in section. 60

In the practice of my invention, the rails, 1, are connected to the ties, 2, by fasteners 1, hereinafter described, and the means for securing the retainer member on one side of the rail to the tie, constitutes itself, at the 65 same time, the retainer member on the other side of the rail.

Referring first to Figs. 1 to 4 inclusive, the retainer member consists of a bar, 12, one end of which is bent into a hook, 12^a, to fit 70 over the edge of the flange, 2^a, of the tie, 2, which is here shown as an old rail inverted. The other end of the retainer member is bent around to form a head, 12^b, with a central opening, similar to that of an eye-bolt. The 75 inner face of the head is recessed, as shown in Fig. 3, to fit over the edge of the flange, 1^a, of the rail, 1. The other member of this fastener consists of a bolt, 13, preferably of rectangular section, which is bent to fit diagonally around and under the tie, and one of its ends is rounded to pass through the eye 80 in the head, 12^b, and is screw threaded for engagement with a nut 13^a. The other end is bent to overlie the edge of the flange, 2^a, 85 of the tie, and present a plane vertical face to the adjacent rail flange, 1^a. It will be obvious that, by tightening up the nut, 13^a, both members will be securely clamped to the tie. By loosening said nut slightly, and 90 by making the top of the recess at a greater angle to the horizontal than the top of the rail flange, as described and claimed in my companion application aforesaid, the rail can be removed by tipping it about the 95 edge of its outer flange.

In the structural modification shown in Figs. 5 to 7 inclusive, the fastener consists of the same retainer member, 12, and of a tie-engaging member, 14, one end of which 100 is rounded to pass through the eye in the head, 12, and receives the nut, 13^a, the other end being bent to overlie the tie flange, as before, but on the same side of the tie as the nut-receiving end, while its body or intermediate portion does not pass around under the tie but is bent to fit up under the flange, 2^a, of the tie, whereby tightening the nut, 13^a, clamps it and the retainer member firmly 105 to the tie. This form of fastener, and 110

those still to be described, are oftener easier to apply than one which comprises a member passing around under the tie, as they can be applied after the tie has been put in place, without lifting it again or digging under it.

In the structural modification shown in Figs. 8 to 11 inclusive, the retainer member, 22, has an eye bolt head, 22^b, at each end, 10 and the tie-engaging member, 24, has both its ends passed through the eyes of said heads, and threaded for engagement with nut 13^a. The middle portion of the member 24 extends across the tie at the other side of 15 the rail, and forms the inner retainer member on that side being joined to the upwardly projecting ends by bent-in portions, which fit under the flange, 2^a, of the tie on opposite sides of its web, in this respect being similar to the body portion of the fastener of Figs. 5 to 7. In some respects, this fastener is a mere duplication of the fastener of said figures. That of Figs. 12 to 14 is very similar to that of Figs. 8 to 11, the 20 only difference being that the middle portion of the tie-engaging member is not continuous like that portion in Figs. 8 to 11, so that there are two separate short inner retainers, each having a portion engaging under 25 the tie flange, 2^a, and an end passed through an eye of the head, 12^b, of the retainer member, and receiving a nut 13^a, similar to the retainer and tie-engaging member of Figs. 5 to 7.

35 I claim as my invention and desire to secure by Letters Patent:

1. A track fastener, for use with ties formed from old rails or of analogous section, comprising a retainer member extending 40 across the tie on one side of the rail and having a recessed portion to receive the rail flange; a combined retainer member and tie-engaging bar, shaped to engage under a part of the tie, and having a portion resting on 45 the top thereof, on the other side of the rail, and having an end engaged with an end of said retainer member; and means for clamping said ends together to secure the fastener to the tie.

50 2. A track fastener, for use with ties formed from old rails or of analogous section, comprising a retainer member extending across the tie on one side of the rail and

having a recessed portion to receive the rail flange, one end of said bar being hook-shaped to engage the edge of the tie-flange and the other end having an opening through it; a tie-engaging member, having one end bent to rest on the tie and form a retainer member on the other side of the 60 rail and its other end passed through the said opening, and threaded; and a nut on said threaded end, the body of said tie-engaging member being bent to fit under the downwardly facing surface of the tie. 65

3. A track fastener, for use with ties formed from old rails or of analogous section, comprising a retainer member, extending across the tie on one side of the rail and having a recessed portion to receive the rail 70 flange, one end of said bar being hook-shaped to engage the edge of the tie-flange and the other end bent to form an eye; a tie-engaging member, having one end bent to rest on the top of the tie on the other 75 side of the rail and on the opposite side of the tie from said eye, and having its other end passed through said eye and threaded to receive a nut, the body of said member being bent to pass diagonally under a part 80 of the tie; and a nut on said threaded end to clamp the fastener in place.

4. A track fastener, for use with ties of rail section, comprising a retainer member extending across the tie and having a recess 85 to overlap the rail flange, a tie-engaging member having its body portion shaped to fit under a downwardly facing surface of the tie, one end bent to overlap the top of the tie, and its other end adapted to be secured to one end of said retainer member. 90

5. A track fastener, for use with ties made of old rails, comprising a retainer member extending across the tie and engaging the rail flange, and means for securing said 95 member in place, consisting of a bar, means to secure said bar at one end to said member, the other end of said bar bent to overlie the tie on the other side of the rail from said member, and the body of said bar being bent to pass around the tie. 100
